KITCHEN IMPLEMENT

Filed July 30, 1929

FIG. 1.

FIG. 2.

FIG. 3.

Inventor

S. E. Agnew

By *Watson C. Coleman* Attorney

UNITED STATES PATENT OFFICE

SAMUEL E. AGNEW, OF DENVER, COLORADO

KITCHEN IMPLEMENT

Application filed July 30, 1929. Serial No. 382,199.

This invention relates to a kitchen implement and it is an object of the invention to provide a device of this kind particularly adapted for use in the cleaning and scraping of pots, pans and sinks.

Another object of the invention is to provide a device of this kind which embodies a blade of desired dimensions provided with a scraping medium and which has its outer corners rounded to assure effective operation over all portions of the sides and bottom of the utensil or device being scraped.

Furthermore, it is an object of the invention to provide a device of this kind comprising means for effectively holding a polishing material, such as steel wool.

The invention consists in the details of construction and in the combination and arrangement of the several parts of my improved kitchen implement whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view in top plan of a kitchen implement constructed in accordance with an embodiment of my invention;

Figure 2 is a sectional view taken substantially on the line 2—2 of Figure 1;

Figure 3 is a sectional view taken substantially on the line 3—3 of Figure 1.

As disclosed in the accompanying drawing, B denotes a substantially flat blade of desired material possessing requisite tenacity and which is substantially in the form of an oblong with its outer corners rounded, as at a. One end portion, or the rear portion as it may be termed, of the blade B at opposite sides of its transverse center has parts rolled inwardly to provide the spaced aligning barrels 1 to provide mountings for the intermediate or base portion 2 of the substantially U-shaped wire frame F. This frame F is formed from

wire of relatively heavy gauge and the free end portions of the side arms 3 of said frame F are threaded through suitably positioned openings 4 in the side marginal portions of the blade B and then returned, as at 5, to overlie the opposed face of the blade B. By this means the frame F is effectively and rigidly held to the blade B.

The central portion of the base member 2 of the frame F is pinched or formed to provide an outstanding double strand shank 6 which is adapted to be engaged within the handle member 7 in a well known manner.

The end portion of the blade B between the barrels 1 is formed to provide a reverted lug or flange 8 having direct contact with the adjacent end of the applied handle 7 thereby further assuring the device in its entirety possessing the requisite stability and rigidity.

The outer or free end portion of the blade B at its central part is provided with a series of transversely disposed slots 9. Each of these slots substantiates the form of a U and the material defined by each of such slots is forced outwardly beyond a face of the blade B to provide effective scraping blades 10 so that the implement can be employed to advantage in effectively scraping pots, pans, sinks and the like, and in this connection it is to be stated that by having the outer corners so rounded the efficiency of the tool is materially increased.

The rear corner portions of the blade B, or its corners adjacent to the frame F, carry the outstanding lugs 11 which provide a mounting for an elongated head 12. This head 12 has extending therefrom and overlying the adjacent face of the blade B holding or clamping arms 14, the free end portions of which being continued by the inwardly disposed penetrating extensions 15. Extending rearwardly from the head 12 is an angularly disposed finger piece 16 providing means whereby the clamping arms 14 will be swung away from the blade B when pressure is exerted upon said finger piece by one of the digits of the hand in engagement with the handle member 7. The clamping arms 14 are constantly urged toward the blade B by the coil spring 17 encircling the head 12. One

end portion of the spring is provided with an extension 18 in engagement with one of the clamping arms 14 while the opposite end of said spring is provided with an extension 19 having contact with the blade B, or more particularly with one of the barrels 1.

When it is desired to employ the implement to polish it is only necessary to swing or move the clamping arms 14 in a direction away from the blade B whereupon a polishing medium, such as steel wool, may be readily disposed over the adjacent face of the blade B, said arms 14 when released effectively engaging said applied medium or wool to maintain the same against displacement. This polishing medium or steel wool is intended to be employed when it is desired to polish various kitchen utensils, sinks or the like.

As particularly illustrated in the accompanying drawing, the arms 14 are arranged in two pairs with the outer portions of the arms of each pair in crossed relation.

When the device is used water will readily run through the slots 9.

From the foregoing description it is thought to be obvious that a kitchen implement constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—
A kitchen implement of the character described comprising a relatively flat blade, a pair of spaced aligned barrels secured to one end of said blade, a U shaped frame secured to said blade and positioned in said barrels, said frame extending rearwardly of said blade intermediate said barrels, scraping means integrally formed with said blade, and a handle secured to the rearward extension of said frame.

In testimony whereof I hereunto affix my signature.

SAMUEL E. AGNEW.
